Attorneys.

UNITED STATES PATENT OFFICE.

BERT M. INGEBRITSON, OF MONTOUR, IOWA.

CLUTCH-PEDAL LOCK.

Application filed February 26, 1926. Serial No. 90,962.

This invention relates to an attachment to be employed in connection with a well known type of vehicle, the primary object of the invention being to provide means whereby the clutch pedal may be held against movement when it has been forced into a position to throw the low gear of the vehicle, into operation.

An important object of the invention is to provide a device of this character which will be automatic in its operation, and one which may be thrown out of use with the minimum amount of exertion on the part of the operator.

A still further object of the invention is to provide a clutch pedal lock which may be readily and easily attached to the usual motor vehicle construction, eliminating the necessity of making alterations in the usual construction to install the device.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a plan view illustrating a transmission housing equipped with a device constructed in accordance with the invention.

Figure 2 is a side elevational view thereof.

Figure 3 is a side elevational view of the attachment, a portion thereof being broken away to illustrate the bifurcated end portion.

Referring to the drawing in detail, the reference character 5 indicates the usual transmission cover that is bolted to the housing 6 by means of the bolts 7 arranged at the corners of the housing and at points adjacent to the edges of the cover.

The device forming the essence of the invention includes an arm 8 which is bolted to the transmission housing by means of bolts 9, the usual bolts 7 arranged intermediate the ends of the transmission cover having been removed and replaced by the bolts 9.

The arm 8 is substantially long so that one end thereof extends beyond one side of the transmission housing where the same is bent

slightly downwardly and laterally as shown by Figure 3.

The outer extremity of the arm 8 is bifurcated the inner wall between the furcations being beveled as at 10 to provide a shoulder 60 for purposes to be hereinafter more fully described.

Operating between the furcations of the bifurcated portion of the arm 8 is a locking arm 11 which is formed with a notch 12 disposed adjacent to the upper end thereof, which notch 12 defines a shoulder 13 to cooperate with the arm 8 in a manner as shown by Figure 3 for holding the arm in its active position.

As shown, the arm is slightly twisted at a point adjacent to its lower end, where the same is formed with an opening to permit the same to be slipped over one end of the connecting link 14 that connects with the 75 lower end of the clutch pedal 15 for transmitting movement to the lever 16 forming a part of the usual motor vehicle construction.

At the upper end of the locking arm 11 is a notch 17 that accommodates one end of the coiled spring 18, the opposite end of the spring being secured to the arm 8 by means of one of the bolts 9.

Thus it will be seen that due to this construction, the coiled spring 18 will normally act to draw the upper end of the locking arm 11 inwardly towards the transmission housing thereby bringing the shoulder 13 into close engagement with the arm 8 to 90 prevent farther downward movement of the locking arm 11.

As before stated, the locking arm 11 is indirectly connected with the clutch pedal 15, so that when the clutch pedal is forced 95 downwardly to throw the low gear into operation, the shoulder 13 is moved to a position to engage the upper edge of the arm 8 and prevent the clutch pedal from automatically moving into the high position, 100 which position the clutch pedal assumes when the operator's foot has been released from the pedal in its low position. Thus it will be obvious that a clutch pedal will be held in its downward position or in a position 105 to hold the low gear in operation, thereby relieving the operator of the responsibility of holding the clutch pedal down while ascending a long grade.

In view of the fact that the pedals of the 110

vehicle move laterally when operated, it will be obvious that by a downward movement of the brake pedal which is arranged adjacent to the arm 11, as shown by Figure 2, and which is indicated by the reference character 19, such lateral movement of the brake pedal will act to throw the arm 11 out of engagement with the arm 8 to the end that the arm 8 will be released and the clutch pedal may move to bring the high gear into operation.

I claim:—

1. A clutch pedal holding device including an arm having pivotal connection with the clutch pedal, said arm being disposed adjacent to the brake pedal of a motor vehicle, means cooperating with the arm for

holding the arm in its active position, and said brake pedal adapted to move laterally to disengage the arm and its securing member.

2. A clutch pedal holding device including an arm pivotally connected with the clutch pedal and disposed in the lateral path of travel of the brake pedal of the vehicle, an arm cooperating with the first mentioned arm to hold the clutch pedal in a predetermined position, and said brake pedal adapted to release the first mentioned arm when the brake pedal is moved slightly downwardly.

In testimony that I claim the foregoing as my own, I have hereto affixed my signature.

BERT M. INGEBRITSON.
